UNITED STATES PATENT OFFICE.

EDWARD T. WEBSTER, OF MILWAUKEE, WISCONSIN.

DESIGN FOR A CLOSET-BOWL.

52,863.

Specification for Design.

Patented Jan. 7, 1919.

Application filed September 11, 1918. Serial No. 253,641. Term of patent 14 years.

To all whom it may concern:

Be it known that I, EDWARD T. WEBSTER, a citizen of the United States, residing at Milwaukee, in the county of Milwaukee and State of Wisconsin, have invented a new, original, and ornamental Design for a Closet-Bowl, of which the following is a specification, reference being had to the accompanying drawing, forming part thereof.

The figure is a bird's-eye perspective view of a closet bowl embodying my design.

I claim:

The ornamental design for a closet bowl as shown.

EDWARD T. WEBSTER.

Witnesses:

CATHERINE SPENCE,
GEO. W. ANDERS.
